(74) *Attorney, Agent, or Firm* — Lisa P. Fulton

(57) **CLAIM**

The ornamental design for the tape application, as shown and described.

DESCRIPTION

FIG. 1 is a perspective view of a tape applicator showing the new design;

FIG. 2 is a side view thereof;

FIG. 3 is a top view thereof;

FIG. 4 is a bottom view thereof;

FIG. 5 is a front view thereof, as taken from the left side of FIG. 2; and,

FIG. 6 is a rear view thereof, as taken from the right side of FIG. 2.

The broken lines shown in the drawings represent portions of the tape applicator that form no part of the claimed design.
